UNITED STATES PATENT OFFICE.

JONAS A. SPARKS, CHARLES E. CLARK, AND WILLIAM M. CLARK, OF ELK CITY, KANSAS.

BRAKE MECHANISM FOR DRYING AND AERATING MACHINES.

1,288,453.

Specification of Letters Patent. Patented Dec. 17, 1918.

Original application filed June 22, 1917, Serial No. 176,449. Divided and this application filed January 16, 1918. Serial No. 212,122.

To all whom it may concern:

Be it known that we, JONAS A. SPARKS, CHARLES E. CLARK, and WILLIAM M. CLARK, citizens of the United States, residing at 5 Elk City, in the county of Montgomery and State of Kansas, have invented certain new and useful Improvements in Brake Mechanism for Drying and Aerating Machines, of which the following is a specification.

10 This invention relates to an improved brake mechanism for drying and aerating machines, being a division of our pending application for drying and aerating machines, filed June 22, 1917, Serial Number 15 176,449.

The invention has as its primary object to provide an arrangement wherein the braking mechanism will be mounted upon the base of the device in position out of the way 20 and adapted to be foot operated for controlling the rotary movement of the basket of the machine.

The invention has as a further object to provide a braking mechanism employing a 25 brake band, and wherein said band will also form a wear strip for the brake lever employed.

And the invention has as a still further object to provide an especially simple form 30 of braking mechanism while, at the same time, said mechanism will prove entirely efficient.

Other and incidental objects will appear as the description proceeds. In the drawings wherein we have illustrated the preferred embodiment of the invention, and wherein similar reference characters designate corresponding parts throughout the several views:

40 Figure 1 is a bottom plan view showing the mounting of the several elements of the brake mechanism upon the base of a drying and aerating machine of the type disclosed in our pending application referred to,

45 Fig. 2 is a sectional view taken on the line 3—3 of Fig. 1 and looking in the direction of the arrows, this view showing the manner in which the brake band employed is secured at its inner end.

50 Fig. 3 is a perspective view illustrating the brake lever in detail, and

55 Fig. 4 is a fragmentary vertical sectional view more particularly showing the disposition of the brake mechanism beneath the base.

In order that the brake mechanism of the present invention may be clearly understood we have, in the drawings, shown such mechanism in connection with a portion of a drying and aerating machine of the type 60 disclosed in our pending application previously identified. This machine includes a base provided with sills 10 having a floor 11 mounted thereon and secured beneath the floor is a cross strip 50. The lower extremity of a driven shaft 41 projects loosely through the floor as well as through this strip. At its upper end, this shaft carries a basket, not shown, adapted to be rotated by the shaft and associated with the lower 65 end of the shaft is the improved brake mechanism for controlling the rotary motion of the shaft. This brake mechanism includes a disk 51 which is detachably fixed to the lower end of the shaft to confront the cross 70 strip 50. Partially surrounding this disk is a brake band 52 secured at one end, as particularly shown in Figs. 2 and 3 of the drawings, to a block 53 mounted beneath the floor 11 of the base at one edge of the 75 cross strip. The opposite extremity of this brake band is connected to a rock lever 54 pivoted upon a hanger bracket 55 secured to the under side of the floor to span the cross strip. The brake band preferably extends the entire length of the inner edge of the said lever to provide a wear strip 56 therefor and the free end of this wear strip is, as shown in detail in Fig. 4, bent around 80 the outer extremity of the lever. Connected at one end to the free extremity of the lever is a spring 57, the opposite end of which is secured in any approved manner to one of the sills 10 of the base. As will be clear, this spring will normally act to pivot the 85 lever 54 for expanding the brake band 52 away from the disk 51 and projecting downwardly from the cross strip 50 to engage the brake band adjacent the inner end of the lever is a stop pin 58 for limiting the 90 lever in its pivotal movement under the influence of the said spring. Mounted upon the floor 11 above the free extremity of the lever 54 is a foot lever 59. This foot lever is pivotally mounted upon a suitable bracket 95 secured to the said floor and is provided with an angularly disposed arm 60 projecting loosely through the floor in front of the free extremity of the lever 54 to engage the wear strip 56 thereon. Accordingly, by de- 100 105 110

pressing the lever 59 the lever 54 will be moved to tighten the brake band 52 about the disk 51 for controlling the rotary movement of the basket 38 or for stopping the basket entirely. Obviously, a brake mechanism of extreme simplicity is thus provided while, at the same time, the said mechanism will prove entirely efficient in use.

2. A device of the character described including a driven shaft, a disk carried by the shaft, a pivotally mounted lever, a brake band arranged about the disk, one extremity of said band being fixed and the other extremity thereof being secured to the inner

In operation, clothes are placed within the basket 38 when the said basket is rotated by means of the crank 21, as previously described. Moisture in the clothes will thus be quickly extracted therefrom. At the same time, rotation of the basket will set up inflowing currents of fresh air through the spout 30 to be discharged directly against the clothes, whence the said air currents will then pass through the discharge spout 31 into the condenser and thence finally discharge through the flue 36. The clothes will accordingly be thoroughly aerated for removing the odors of any cleaning fluids therefrom. As is well known, such cleaning fluids are usually of a volatile nature and the condenser 32 is accordingly provided so that vapors from the said fluids may be connected within the said condenser, to be reclaimed thereby.

Having thus described the invention, what is claimed as new is:

1. In mechanism of the character described, a driven shaft, a friction disk, a rock lever, a brake band arranged to operate with said disk and secured to the said lever to provide a wear strip therefor and a second lever mounted to engage the wear strip for pivoting the first lever to

2. A device of the character described including a driven shaft, a disk carried by the shaft, a pivotally mounted lever, a brake band arranged about the disk, one extremity of said band being fixed and the other extremity thereof being secured to the inner extremity of said lever at one side of its pivot point, the latter extremity of the band being extended along the lever to the opposite side of its pivot point to provide a wear strip for the lever, and means arranged to coöperate with the lever at the latter side of its pivot point and engaging said wear strip for tensioning the brake band about the disk to control the rotary movement of the shaft. 45 50 55

3. In mechanism of the character described, the combination with a base, of a driven shaft projecting beneath the base, a pivoted lever mounted beneath the base, a brake band connected with the said lever and arranged to coöperate with said shaft, and a second lever mounted above the base and projecting therebeneath to coöperate with the first lever, the second lever being operable for pivoting the first lever to tension the brake band about the shaft for controlling the rotary movement of the shaft.

In testimony whereof we affix our signatures.

JONAS A. SPARKS. [L. S.]
CHARLES E. CLARK. [L. S.]
WILLIAM M. CLARK. [L. S.]
